(57) **CLAIM**

The ornamental design for a garden bed, as shown and described.

DESCRIPTION

FIG. 1 is a top perspective view of a garden bed;

FIG. 2 is a bottom perspective view of the garden bed shown in FIG. 1;

FIG. 3 is front elevational view thereof with the back side being identical;

FIG. 4 is a top plan view thereof;

FIG. 5 is a bottom plan view thereof; and,

FIG. 6 is a right side elevational view thereof with the left side being identical.

The broken lines in the drawings form no part of the claimed design.

1 Claim, 6 Drawing Sheets
